CLAIM

The ornamental design for a food container as shown and described.

DESCRIPTION

FIG. 1 is a top perspective view of a first embodiment of a food container showing the new design;

FIG. 2 is a bottom perspective view thereof;

FIG. 3 is a top plan view thereof;

FIG. 4 is a bottom plan view thereof;

FIG. 5 is a left side elevation view thereof (the right side elevation view is a mirror image of FIG. 5);

FIG. 6 is a front elevation view thereof;

FIG. 7 is a rear elevation view thereof;

FIG. 8 is a top perspective view of a second embodiment of a food container showing my new design;

FIG. 9 is a bottom perspective view thereof;

FIG. 10 is a top plan view thereof;

FIG. 11 is a bottom plan view thereof;

FIG. 12 is a left side elevation view thereof (the right side elevation view is a mirror image of FIG. 12);

FIG. 13 is a front elevation view thereof; and,

FIG. 14 is a rear elevation view thereof.

The dash-dash type broken lines shown in the drawing views are included for the purpose of showing environmental subject matter that forms no part of the claimed design. The dash-dot-dash broken lines in the drawings, define the bounds of the claimed design and form no part thereof.

1 Claim, 14 Drawing Sheets
